OBSTETRICAL FORCEPS

Wallace B. Shute, Ottawa, Ontario, Canada

Application September 13, 1957, Serial No. 683,777

6 Claims. (Cl. 128—323)

This invention relates to obstetrical forceps and in particular to obstetrical forceps having a novel linkage between the two cooperating members, and is an improvement in the invention described and claimed in my prior U. S. Patent No. 2,757,673, issued to me on August 7th, 1956.

According to one aspect of the invention, a pair of obstetrical forceps comprises two main members adapted to move in parallel relation to one another, each of said members having a handle at one end thereof and a blade at the end remote from said handle, a bore within a first of said handles, a screw-threaded member adapted to move longitudinally within said bore, said threaded member having an inner end and an outer end, a recess in said first handle arranged at right angles to the longitudinal axis of said bore and communicating therewith, a wheel located within said recess, a threaded axial bore in said wheel for engagement with said threaded member, means located in a second of said handles co-operating with said outer end of said threaded member for bringing about detachable engagement of said second handle with said threaded member, and means located in said first handle and co-operating with said inner end of said threaded member to prevent relative rotation of said first handle and said threaded member.

According to another aspect of the invention, a pair of obstetrical forceps comprises two main members adapted to move in parallel relation to one another, each of said members having a handle at one end thereof and a blade at the end remote from said handle, a bore within a first of said handles, a screw-threaded member adapted to move longitudinally within said bore, said threaded member having an inner end and an outer end, a recess in said first handle arranged at right angles to the longitudinal axis of said bore and communicating therewith, a wheel located within said recess, a threaded axial bore in said wheel for engagement with said threaded member, a recess located in a second of said handles adapted to receive said outer end of said threaded member, a slot in said second handle, a movable stud in said slot maintaining said outer end of said threaded member in said last mentioned recess, and means located in said first handle and co-operating with said inner end of said threaded member to prevent relative rotation of said first handle and said threaded member.

A still further aspect of the invention resides in a pair of obstetrical forceps comprising two main members adapted to move in parallel relation to one another, each of said members having a handle at one end thereof and a blade at the end remote from said handle, a bore within a first of said handles, a screw-threaded member adapted to move longitudinally within said bore, said threaded member having an inner end and an outer end, a head on said outer end of said threaded member, a recess in said first handle arranged at right angles to the longitudinal axis of said bore and communicating therewith, a wheel located within said recess, a threaded axial bore in said wheel for engagement with said threaded

member, a recess located in a second of said handles adapted to receive said head, a slot in said second handle, a movable stud in said slot maintaining said outer end of said threaded member in said last mentioned recess, and means located in said first handle and co-operating with said inner end of said threaded member to prevent relative rotation of said first handle and said threaded member.

The invention is illustrated in the accompanying drawing in which:

Figure 1 is a part sectional front elevation of a pair of obstetrical forceps embodying the invention;

Figure 2 is a section taken on the line 2—2 of Figure 1; and

Figure 3 is a section taken on the line 3—3 of Figure 1.

Referring now to Figure 1, it will be seen that the obstetrical forceps include a pair of main members indicated generally at 1, 2, each having handle portions 3, 4 and blade portions 5, 6 respectively. The outer end of each handle portion 3, 4 is provided with a recess 7, 8 respectively.

Handle portion 4 of the main member 2 is provided with a pistol grip 9 having an axial bore 10 formed therein and a second recess 11 extending across said bore at right angles thereto.

The handle portion 3 of the main member 1 is provided with a curved finger grip 12 projecting therefrom at substantially right angles thereto whilst the wall of the handle portion 3 is also provided with a curved strap 13 projecting inwardly into the recess 7. Located between the strap 13 and an end wall 14 of the recess 7, is an elongated head 15 of a threaded screw 16 adapted to engage with a correspondingly internally threaded thumb-wheel 17 housed within the recess 11 in the main member 2 and having its peripheral portion substantially projecting therefrom (see Figure 2). As will be seen more clearly in Figure 1, the pistol grip 9 is provided with a lug 18 adapted to engage with a keyway 19 formed in the screw 16, the co-operation between said lug 18 and the key-way 19 preventing relative rotation between said screw 16 and the pistol grip 9.

It will be noted, particularly from Figures 1 and 3, that the elongated head 15 of the screw 16 is provided with a lip 20 at one end thereof which, when said head is placed in position between the end wall 14 and strap 13, engages with a slot 21 formed in the base of said strap.

The handle portion 3 of the main member 1, as will be seen from Figures 1 and 3, is provided with an elongated slot 22 in which a stud 23 is freely movable, said stud, when in its normal position, being adapted to maintain the head 15 of the screw 16 between the strap 13 and the end wall 14 of the recess 7.

From the above description it will be appreciated that due to the respective engagements of the handle portions 3, 4 with the screw 16, the two main members 1 and 2 will be maintained in substantially fixed relation to one another. However, when it is desired that the blades 5, 6 should be moved, substantially parallel, towards or away from one another, adjustment of the thumb-wheel 17 will cause the screw 16 to advance or retreat thus bringing about parallel movement of the blades easily and swiftly.

On the other hand, when it is desired to sterilize or clean the instrument, the components thereof can be dismantled with utmost ease by moving the stud 23 within its slot 22 thereby permitting the main member 1 to be disengaged from the head 15 of the screw 16. Thus the two main members will be completely free of one another.

Thereafter, by rotation of the screw 16, the latter can be disengaged from the pistol grip 9 and the thumb-

wheel 17 and when this occurs, said thumb-wheel 17 can also be removed from its associated recess 11. Thus for cleaning purposes the assembly can be broken down into four main components.

It will also be appreciated that due to the engagement of the lug 18 with the keyway 19 of the screw, no rocking movement of the components can occur, and thus no undue pressure can be exerted on the tip of the blades thereby obviating any crushing effect which would be liable to occur if the blades did not automatically move parallel to one another; thus, the parallel movement of the two main members towards and away from one another is achieved in a smooth and harmonious manner.

It is within the ambit of the invention to omit the lip 20 from the elongated head 15 and, in consequence, its associated slot 21, too, would be omitted. Thus, the elongated head 15 will be a relatively snug fit within its associated recess. In this case, it has been found by experience that the stud 23 operates perfectly satisfactorily to maintain the head 15 in position.

I claim:

1. A pair of obstetrical forceps comprising two main members adapted to move in parallel relation to one another, each of said members having a handle at one end thereof and a blade at the end remote from said handle, a bore within a first of said handles, a screw-threaded member adapted to move longitudinally within said bore, said threaded member having an inner end and an outer end, a recess in said first handle arranged at right angles to the longitudinal axis of said bore and communicating therewith, a wheel located within said recess, a threaded axial bore in said wheel for engagement with said threaded member, means located in a second of said handles cooperating with said outer end of said threaded member for bringing about detachable engagement of said second handle with said threaded member, and means located in said first handle and co-operating with said inner end of said threaded member to prevent relative rotation of said first handle and said threaded member.

2. A pair of obstetrical forceps comprising two main members adapted to move in parallel relation to one another, each of said members having a handle at one end thereof and a blade at the end remote from said handle, a bore within a first of said handles, a screw-threaded member adapted to move longitudinally within said bore, said threaded member having an inner end and an outer end, a recess in said first handle arranged at right angles to the longitudinal axis of said bore and communicating therewith, a wheel located within said recess, a threaded axial bore in said wheel for engagement with said threaded member, a recess located in a second of said handles adapted to receive said outer end of said threaded member, a slot in said second handle, a movable stud in said slot maintaining said outer end of said threaded member in said last mentioned recess, and means located in said first handle and co-operating with said inner end of said threaded member to prevent relative rotation of said first handle and said threaded member.

3. A pair of obstetrical forceps comprising two main members adapted to move in parallel relation to one another, each of said members having a handle at one end thereof and a blade at the end remote from said handle, a bore within a first of said handles, a screw-threaded member adapted to move longitudinally within said bore, said threaded member having an inner end and an outer end, a head on said outer end of said threaded member, a recess in said first handle arranged at right angles to the longitudinal axis of said bore and communicating therewith, a wheel located within said recess, a threaded axial bore in said wheel for engagement with said threaded member, a recess located in a second of said handles adapted to receive said head, a slot in said second handle, a movable stud in said slot maintaining

ing said outer end of said threaded member in said last mentioned recess, and means located in said first handle and co-operating with said inner end of said threaded member to prevent relative rotation of said first handle and said threaded member.

4. A pair of obstetrical forceps comprising two main members adapted to move in parallel relation to one another, each of said members having a handle at one end thereof and a blade at the end remote from said handle, a bore within a first of said handles, a screw-threaded member adapted to move longitudinally within said bore, said threaded member having an inner end and an outer end, a head on said outer end of said threaded member, a keyway in said threaded member, a recess in said first handle arranged at right angles to the longitudinal axis of said bore and communicating therewith, a wheel located within said recess, a threaded axial bore in said wheel for engagement with said threaded member, a recess located in a second of said handles adapted to receive said head, a slot in said second handle a movable stud in said slot maintaining said outer end of said threaded member in said last mentioned recess, and means located in said first handle and co-operating with said keyway to prevent relative rotation of said first handle and said threaded member.

5. A pair of obstetrical forceps comprising two main members adapted to move in parallel relation to one another, each of said members having a handle at one end thereof and a blade at the end remote from said handle, a bore within a first of said handles, a screw-threaded member adapted to move longitudinally within said bore, said threaded member having an inner end and an outer end, a head on said outer end of said threaded member, a lip projecting from said head, a keyway in said threaded member, a recess in said first handle arranged at right angles to the longitudinal axis of said bore and communicating therewith, a wheel located within said recess, a threaded axial bore in said wheel for engagement with said threaded member, a recess located in a second of said handles adapted to receive said head, a slot in said recess located in said second handle to receive said lip, a slot in said second handle, a movable stud in said last mentioned slot maintaining said outer end of said threaded member in said last mentioned recess, and means located in said first handle and co-operating with said keyway to prevent relative rotation of said first handle and said threaded member.

6. A pair of obstetrical forceps comprising two main members adapted to move in parallel relation to one another, each of said members having a handle at one end thereof and a blade at the end remote from said handle, a bore within a first of said handles, a screw-threaded member adapted to move longitudinally within said bore, said threaded member having an inner end and an outer end, a head on said outer end of said threaded member, a lip projecting from said head, a keyway in said threaded member, a recess in said first handle arranged at right angles to the longitudinal axis of said bore and communicating therewith, a wheel located within said recess, a threaded axial bore in said wheel for engagement with said threaded member, a recess located in a second of said handles adapted to receive said head, a slot in said recess located in said second handle to receive said lip, a slot in said second handle, a movable stud in said last mentioned slot maintaining said outer end of said threaded member in said last mentioned recess, and a lug located in said first handle and co-operating with said keyway to prevent relative rotation of said first handle and said threaded member.
